UNITED STATES PATENT OFFICE.

VOJTECH CIZEK, OF ASTORIA, NEW YORK.

ROTARY INTERNAL-COMBUSTION ENGINE.

Application filed November 16, 1927. Serial No. 233,663.

The present invention relates to rotary internal combustion engines and more particularly to that type having a plurality of cylinders and working pistons reciprocating therein, and in which the working cylinders partake of a continuous rotary motion about a fixed axis as the working pistons reciprocate therein.

In one type of these engines the piston energy is converted into a rotary drive of the engine by a plurality of cams, usually stationary, co-operating with as many rollers as there are pistons in the engine, each roller being carried on a separate spindle. Considerable difficulties have been experienced with these constructions not only for the reason that the unduly high number of rollers are apt to wear out the cams co-operating therewith, but also due to the fact that these engines employ as many cranks as there are cylinders contained therein. In addition links, pins, etc. are used for connection between the elements mentioned so that the structures are too complicated for the purpose for which they are intended.

The main object of the present invention is to so construct a rotary engine of the type mentioned, in which it is feasible to eliminate parts heretofore regarded as necessary, whereby not only the weight of the engine is cut down to a minimum but the life of the engine is considerably extended.

A further object of the invention is to so arrange the cylinders of the engine and to so combine the same with the other elements thereof that, for instance, in a four-cylinder engine four explosions or power strokes are obtained during each revolution of the rotary support of the cylinders; in other words as many power strokes are obtained during each revolution as there are cylinders provided therein.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the

spirit or sacrificing any of the advantages 55 of the invention.

One of the many possible embodiments of the invention is illustrated in the accompanying drawings, in which:

Figure 1 is a central vertical section taken 60 through an engine constructed in accordance with the present invention; Fig. 2 is a section taken through the cylinders and working pistons of the engine; Fig. 3 is a side elevation of the cam tracks of the engine 65 and the elements co-operating therewith; Figs. 4 to 7, inclusive, are diagrammatic views of the positions assumed by certain parts of the engine during the various intervals of one cycle; Fig. 8 is a central vertical 70 section taken through a modified engine; and Fig. 9 is a transverse section taken through Fig. 8.

In accordance with the invention a rotary support is employed, to which is fixed 75 a plurality of cylinders, in each of which is arranged a piston. These pistons are connected to an oscillatable shaft, provided with a crank, the support being also provided with a crank. The two cranks are 80 connected each by a link with a spindle, on which are mounted two rollers, each of said rollers co-operating with a cam track, so that the reciprocating motion of the pistons causes the support and the cylinders 85 mounted thereon to rotate. This arrangement permits rotary motion to be taken directly off from the rotating support.

Referring now first to Figs. 1 to 7, inclusive, of the drawings, the numeral 10 indicates a casing, provided with two aligned tubular sections 11 and 12. The tubular section 11 is rotatably mounted in a bearing structure 13 of a stationary housing 14, carried by a standard 15 which rises from a base 16. 90 The tubular section 12, which constitutes a hollow shaft, is rotatably mounted in a standard 17, also rising from the said base. The element 12 constitutes the driven shaft 95 of the engine, as will hereinafter more fully appear. To the casing 10 are fixed, in a plane at right angles to the shaft 12, two pairs of cylinders 18, the cylinders of each pair being aligned with their open ends juxtaposed. The cylinders of one pair are denoted in Fig. 2 of the drawings by the numerals I and II, and the cylinders of the other pair are denoted by the numerals III 105

and IV. In each cylinder is arranged to reciprocate a piston 19. The pistons of the cylinder pair I and II are connected by oppositely extending pitmen 20 to a pin 21, and the pistons of the cylinder pair III and IV are connected by oppositely extending pitmen 22 to a pin 23. These pins are carried upon the oppositely projecting ends 24 and 25, respectively, of a lever arm 26, which is fixed to a centrally arranged crank-shaft 27, disposed in alignment with the shaft 12 above referred to. The crank-shaft 27 is oscillatably mounted in bearings 27' in the tubular extension 11 of the casing 15 or cylinder support 10.

Each cylinder is provided with an inlet port and with an exhaust port, not shown as the construction of the same is well known, and these ports are controlled by inlet and outlet valves, which have not been shown because their construction and operation is well understood by those versed in the art. Attention is, however, called to the fact that the combustible mixture is led 20 to the cylinders through the hollow shaft 12, which communicates with an intake manifold 28, leading to the several cylinders of the engine, the said intake manifold being fixed to the head 29 of the cylinder 30 support 10. The exhaust port of each cylinder opens directly to the atmosphere.

The inlet and outlet valves of the several cylinders are actuated by cams 30 which are fixed to a cam shaft 31, the latter being rotatably mounted in bearings 32 on the cylinder support 10 and having mounted thereon a bevel gear 33, in mesh with a similar gear 34 on a shaft 35. This shaft is also mounted on the cylinder support and has keyed to it a gear 36, in mesh with a stationary gear 37, the latter being fixed to the stationary housing 14 above referred to. In order to properly balance the shaft 31, it is driven at both of its ends, and for this purpose obviously it has on each of its ends a bevel gear 33, associated with the elements above described. The connection between the cams and the valves has not been shown, the same being well known.

Due to the arrangement of the cylinders and pistons and the connections above specified, and furthermore also due to the timing of the inlet and outlet valves, the several phases of the cycle of operation in the cylinders of the engine are as follows, reference being had to Fig. 2 of the drawings: When the piston in the cylinder I is at the beginning of its explosion stroke, the piston in the cylinder II is at the beginning of its compression stroke. At the same time the piston in the cylinder III is at the beginning of its intake stroke and the piston in the cylinder IV is at the beginning of its exhaust stroke.

To the crank-shaft 27 is fixed a crank 38,

disposed within the stationary housing 14, and to the cylinder support 10 is fixed a crank 39, also within the housing 14. The crank 38 is connected by means of a link 40 with a spindle 41, and the latter is connected 70 by means of a link 42 with the crank 39 (Fig. 3). On this spindle are mounted two rollers 43 and 44, the roller 43 co-operating with a cam track 45 and the roller 44 with a cam track 46. These two tracks are fixed 75 within the stationary housing 14. As appears from Fig. 3 of the drawings, both tracks are oblong in configuration, the track 45 being what may be termed an inner track, that is to say a cam groove, and the track 80 46 being an outer track, that is a true cam.

The two tracks are parallel throughout their lengths, and, if divided on a circle into sections of 45°, as indicated in Fig. 3 of the drawings, it will be noted that from the 85 starting point 47 of track 45 the latter has through the first 90° in the direction of the arrow shown in Fig. 3 of the drawings an uninterrupted curvature. In the next 45° it is curved toward the longitudinal axis 90 of the crank-shaft, thence through an arc of the next 45° it is substantially in the form of a sinusoidal curve up to the point 48. From the point 48 back to the point 47, that is to say through an arc of the next 95 180°, the configuration of the track is the same as that described in connection with the first 180°.

The operation of the engine is as follows: Referring to Fig. 2 of the drawings, it will 100 be seen that the cylinders are in horizontal positions and in a position in which an explosion is occurring in the cylinder I. The cranks connected with the crank-shaft of the engine and with the cylinder supporting 105 casing are then in the positions shown in Fig. 4 of the drawings, and the rollers connected therewith are in relation to the cam tracks of the device also in the positions shown in Fig. 4 of the drawings. The explosion in the cylinder I, through the piston 110 therein and the connection thereof with the crank-shaft, imparts to the crank-shaft a turn of 90°, carrying with it the rollers and the cylinder supporting casing, the latter also 115 moving through an arc of 90°. Consequently the crank-shaft during the first explosion moves 180°, the elements being then in the positions shown in Fig. 5 of the drawings. In the meantime the charge in piston II has 120 been compressed and the cylinders are in vertical positions. When now an explosion occurs in cylinder II all of the pistons of the device move in directions opposite to that in which they were moving during the 125 first explosion, the result being that the crank-shaft moves 90° in the opposite direction. Inasmuch as, however, the rollers are disposed on the cam tracks, the cylinder supporting casing 10 is caused to move 90° 130

2. A rotary explosive engine comprising a stator having two cam tracks, a rotor supporting two pairs of parallel cylinders, the open ends of each pair of cylinders being juxtaposed, an oscillatable crank-shaft on said rotor, a piston in each cylinder, a connection between said piston and said crank-shaft causing the latter to turn 90° during an explosion in a cylinder in a direction opposite to that in which it turned during the previous explosion in a cylinder in the series, a crank fixed to said rotor, a spindle, two rollers on said spindle in engagement with said cam tracks, and two links connecting said spindle with said crank-shaft and with the crank on said rotor.
3. In a rotary explosive engine according to claim 1, said cam tracks being alike in configuration and arranged in parallel relation.
4. In a rotary explosive engine according to claim 2, said cam tracks being alike in configuration and arranged in parallel relation.
5. An internal combustion engine comprising a support, a pair of cylinders thereon, a piston in each cylinder, a crank-shaft, a connection between said pistons and said crank-shaft causing the latter to oscillate, a driven shaft, and means for converting the oscillating motion of said crank-shaft into a rotary motion of said driven shaft including a pair of cam tracks, a crank on said support, a spindle, two rollers on said spindle in engagement with said cam tracks, and two links connecting said spindle with said crank shaft and with the crank on said support.

Signed at New York, in the county of New York, and State of New York, this 20th day of October, A. D. 1927.
